UNITED STATES PATENT OFFICE.

JEAN PIERRE LEONARD, OF FIVE MILE, OHIO.

IMPROVEMENT IN GRAIN-CLEANERS.

Specification forming part of Letters Patent No. 133,041, dated November 12, 1872.

To all whom it may concern:

Be it known that I, JEAN PIERRE LEONARD, of Five Mile, Brown county, Ohio, have invented a Grain Cleaner and Separator, of which the following is a specification:

Nature and Objects of the Invention.

This invention relates to a simple and portable machine or mill for effectually cleaning wheat or other grain and separating cheat or other refuse grain therefrom.

Description of the Accompanying Drawing.

Figure 1 is a side elevation of my separator. Fig. 2 is a horizontal section in the line X X. Fig. 3 is a vertical section in the line Y Y.

The inclosing case or shell consists of a drum or wind-box, A, from one side of which projects tangentially a spout, B, open at both ends. The drum A is traversed axially by a shaft, C, armed with beaters D, constituting a fan; and this fan is rotated by a crank, E, journaled in frame F, and whose shaft G has a bevel-wheel, H, that gears with a bevel-pinion, I, upon the upper end of shaft C. A hopper, J, on the top of spout B admits the uncleaned grain through orifice K into a screen, L, suspended by links M M', and subjected to a violent shaking motion by tabs N, that project from crank-shaft G, through the medium of bell-crank O and bent rod P. The opposite end of the screen (being that most remote from fan) is entirely open, and is attached by rod Q to retracting-spring R. That portion T of the top of the spout to which the hopper J is attached is removable, and is se-

cured in place by means of bolts U passing through ears V that project from the spout. The removability of the hopper J and its base T enables the inspection and temporary removal or substitution of different grades of screens or riddles. A slide, W, enables the adjustment of the passage of the hopper. That portion of the spout-floor beyond the hole S is a sliding piece, X. A register, Y, pivoted underneath the drum, enables the regulation of the blast by contraction or expansion of the inlet Z.

Operation.

Uncleaned grain being fed into hopper J descends through orifice K into the screen L, in which passage—encountering the blast in flank—the chaff is thereby driven out through the open spout B. The cheat and other small refuse, too heavy for removal by the blast, drop through the screen and out through hole S in the spout-bottom, while the good grain, being carried slowly forward, escapes into the adjustable floor of the spout at X.

I claim as new and of my invention—

The described arrangement of blast A B C D Z, hopper J K W, screen L M M', and adjustable floor X with the described agitating and regulating devices, as and for the purpose explained.

In testimony of which invention I hereunto set my hand.

JEAN PIERRE LEONARD.
